CLAIM

The ornamental design for an all-in-one cleaning tool, as shown and described.

DESCRIPTION

FIG. 1 is a perspective view of an all-in-one cleaning tool showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is an underside view thereof.

The broken lines shown in FIG. 7 represent twin tracks, which form no part of the claimed design.

1 Claim, 7 Drawing Sheets(56)
